UNITED STATES PATENT OFFICE.

CHARLES G. SHEPARD AND PETER ADAMS, OF BUFFALO, NEW YORK; SAID
ADAMS ASSIGNOR TO WALTER J. SHEPARD, OF SAME PLACE.

ICE-CREAM FREEZER.

SPECIFICATION forming part of Letters Patent No. 410,773, dated September 10, 1889.

Application filed January 19, 1888. Serial No. 261,219. (No model.)

To all whom it may concern:

Be it known that we, CHARLES G. SHEPARD and PETER ADAMS, of the city of Buffalo, in the county of Erie and State of New York, have invented new and useful Improvements in Ice-Cream Freezers, of which the following is a specification.

This invention relates more particularly to improvements in that class of ice-cream freezers which are provided with a hinged or movable top frame carrying a part of the actuating mechanism whereby the cream can or vessel is rotated, and which frame can be swung upwardly out of the way, so as to permit the removal and replacement of the cream-can.

Our invention has for its object to improve the construction of the hinged top frame, so that the driving-shaft and connecting parts can be readily removed for cleaning the same, also to provide the freezer with efficient means whereby the freezing-mixture is excluded from the actuating-gearing, and also to improve the fastening whereby the movable top frame is locked in position.

The invention consists of the improvements which will be hereinafter fully set forth, and pointed out in the claims.

In the accompanying drawings, Figure 1 is a sectional elevation of an ice-cream freezer provided with our improvements. Fig. 2 is a front elevation of the fastening whereby the free end of the hinged top frame is secured to the tub of the freezer. Fig. 3 is a vertical section in line $x-x$, Fig. 1. Fig. 4 is a bottom plan view of the top frame of the freezer and connecting parts.

Like letters of reference refer to like parts in the several figures.

A represents the outer wooden tub or vessel, which receives the cream-can B and the freezing-mixture. The cream-can is provided at its bottom with a stud or journal, which turns in a socket or bearing arranged in the bottom of the wooden tub in a well-known manner.

C is the cover of the cream-can, and D the vertical shaft or spindle to which the dasher arms or blades are attached, and which is supported at its lower end in a bearing formed in the bottom of the cream-can and passing

with its upper portion through an opening d, formed centrally in the cover C.

E represents the movable top frame of the freezer, in which the horizontal actuating-shaft f is supported. The latter is provided at its inner end with a bevel-wheel f', which meshes with a gear-rim f², formed on or secured to the upper side of the cover C of the cream-can and at its outer end with a detachable hand-crank for turning the shaft.

The movable top frame is composed of a central portion or plate e and radial supporting-arms e' e' and e². The arms e' are journaled in bearings g, secured to the upper end of the tub A in the ordinary manner, and the arm e² is detachably secured to the tub, so that upon releasing its fastening the frame E can be swung upwardly on the arms e', so as to clear the upper end of the tub. The outer portion e³ of the arm e² is inclined forwardly and downwardly, and in this inclined portion is formed an oblique bearing h, in which the outer portion of the shaft f is arranged, as represented in Fig. 1. The inner portion of the shaft is journaled in a divided bearing h', composed of a lug h², arranged on the under side of the arm e², and a removable cap h³. The latter is secured to the lug by a screw i. The cap is provided at its ends with lips or flanges i', which overlap the ends of the lug and hold the plate against turning on the screw i.

K K represent collars formed on the shaft f between the bearings thereof, so as to hold the shaft against lengthwise movement. By arranging the outer bearing h obliquely the lower portion of the bearing is located in advance of or beyond the upper portion thereof instead of directly underneath the same, whereby the opening of the bearing is rendered elliptical or elongated in the direction of the inclined portion of the frame, while it is practically circular in a plane at right angles to the actuating-shaft. This construction forms a sufficiently snug bearing to prevent vertical play of the shaft and permits at the same time the shaft to be tilted downwardly upon raising the top frame and removing the cap of the inner bearing, thereby allowing the shaft to be drawn inwardly out of the outer bearing upon detaching the

hand-crank. By constructing the outer bearing in this manner the same may be cast complete in one piece with the top frame without the necessity of coring or drilling, 5 and but one of the bearings need be divided or provided with a removable cap, thereby simplifying the construction of the top frame and reducing its cost and facilitating the removal and replacement of the shaft when 10 it is desired to clean the machine. The shaft is attached to the top plate by removing its crank, passing the outer end of the shaft through the oblique outer bearing, then placing the inner portion of the shaft into the 15 inner bearing and securing the cap of the same in place.

L represents a metallic plate secured to the side of the tub A near the upper edge thereof, and provided with a notch or recess 20 l, which receives a lip l', formed at the outer end of the arm e² of the top frame, and whereby said arm is held against lateral movement.

M is a hook pivoted to the plate L and engaging over a hook-shaped lug m, formed on 25 the lip l' of the arm e², and whereby the latter is secured in its seat in the plate L.

n represents a dog or pawl pivoted to the plate L and bearing against the rear side of the hook M, so as to prevent the accidental 30 disengagement of the hook from the arm e². Upon throwing the catch n back the hook M can be released from the lug m.

By attaching the parts of the fastening to the metallic plate L the formation of the usual 35 notch in the upper edge of the tub for receiving the end of the arm e² is dispensed with. A more rigid lock is also obtained by this construction, as the notch or socket in the metallic plate does not wear and allow 40 the arm to become loose in time, which is the case when the socket is formed directly in the wooden tub, because the sides of the socket are caused to become soft and decay by contact with the freezing-mixture and allow the socket to enlarge.

The upper square end of the dasher-spindle D is inserted in a correspondingly-shaped opening in the top frame in the customary manner and forms a support upon which the 45 upper end of the cream-can turns.

P is an upwardly-projecting collar or annular flange formed on the upper side of the cream-can cover at a distance inwardly from the marginal flange of the cover and surrounding the gear-rim f².

O represents a depending annular flange or shield formed on the under side of the cen-

tral portion e of the top frame and overlapping the collar P. The shield, in conjunction with the collar, forms a guard, which 60 prevents the freezing-mixture working over the top of the can from entering between the gearing and interfering with the easy operation of the freezer.

By arranging the collar and shield above 65 and within the upper marginal edge of the can the freezing-mixture can be packed to the extreme top of the can without danger of interfering with the actuating-gearing, thereby enabling the full capacity of the cream-can to be utilized. The collar of the cream-can cover also forms a convenient handle for manipulating the cream-can.

We claim as our invention—

1. The combination, with the tub, the cream-can provided with a gear-rim, and the actuating-shaft provided with a wheel, of a removable top frame provided with a divided inner bearing and a solid oblique outer bearing, in which the shaft is journaled, whereby 80 the shaft can be tilted and withdrawn from the solid outer bearing upon removing the cap of the inner bearing, substantially as set forth.

2. The combination, with the tub, the cream-can provided with a gear-rim, and the actuating-shaft provided with a gear-wheel, of a removable top frame provided with a divided inner bearing and with an outer bearing having its lower portion arranged outwardly 90 beyond its upper portion, substantially as set forth.

3. The combination, with the tub, the cream-can, and its cover provided with a gear-rim, of an upwardly-projecting-collar secured on 95 the cover within the marginal edge thereof and surrounding said gear-rim, a removable top frame adapted to be secured to the tub, a shaft journaled in said frame and provided with a gear-wheel meshing with the 100 gear-rim of the cream-can and rotating the same, and a depending annular shield arranged on the under side of the top frame above and inside of the marginal edge of the cream-can and around the collar thereof, substantially as set forth.

Witness our hands this 14th day of January, 1888.
